McCLURE AND ONE-THIRD TO FRANKLIN TRITT LE FEVRE, BOTH OF SÉBRING,
OHIO.

WARNING SYSTEM FOR GAS OR OIL.

1,326,578.

Specification of Letters Patent. Patented Dec. 30, 1919.

Application filed January 31, 1918. Serial No. 214,666.

To all whom it may concern:

Be it known that I, JESSE T. CURTIS, a citizen of the United States, residing at Sebring, in the county of Mahoning and State of Ohio, have invented a new and useful Warning System for Gas or Oil, of which the following is a specification.

The device forming the subject matter of this application is adapted to be employed for giving a signal, either visible or audible, when the liquid in a tank has been depleted to a predetermined amount, the structure being of peculiar utility when used in connection with the fuel tank of an automobile, although the invention is not confined to this specific use.

The invention aims to provide a simple but efficient means whereby a circuit may be closed, to actuate a signal, when the liquid in a tank has been depleted to a fixed extent.

It is within the province of the disclosure to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings:

Figure 1 shows in vertical longitudinal section, a device constructed in accordance with the present invention; parts appearing in elevation, and the circuit being diagrammatically shown;

Fig. 2 is an elevation showing a casing in which the electric lamps may be housed;

Fig. 3 is a detail enlarged from Fig. 1 and showing the bridging member and the part whereon the bridging member is carried;

Fig. 4 is a fragmental elevation showing a modification in the mechanism which carries the float.

The numeral 1 marks a tank having a top 2 provided with a closure 3 which may be threaded at 4 into the top, the closure including an upstanding tubular neck 5 upon which a cap 6 may be threaded as shown at 7, the cap serving to house certain of the

working parts of the structure. A barrel 8, 55 made of insulating material, is seated in the neck 5. Contact terminals 9 are mounted on the upper end of the barrel 8 and include extensions 10 prolonged downwardly into the barrel. Insulating bushings 11 are carried by the neck 5 of the closure 3 and extend into the barrel 8 to hold the latter in the neck 5. Binding posts 12 are threaded into the bushings 11 and engage the extensions 10 of the contact terminals 9. Clamp 65 nuts 14 are mounted on the outer ends of the binding posts 12 and engage the ends of a conductor 15. In the circuit which includes the conductor 15, are interposed signals of any desired kind. If preferred, one 70 signal may be in the form of an electric lamp 16 mounted within a receptacle 17 having a glass front 18 provided with an inscription 19. The receptacle 17 may be mounted upon any accessible portion of an 75 automobile and the inscription 19 may be changed, depending upon the nature of the liquid which is contained in the tank 1. An audible signal, such as a bell 20, may be interposed in the conductor 15, and the numeral 21 denotes a battery or other suitable source of electrical energy interposed in the circuit of which the conductor 15 forms a part. A guide tube 24 extends downwardly into the tank 1 and upwardly through the 80 closure 3, the guide tube being secured in the barrel 8. Between the upper end of the guide tube 24 and the top of the barrel, there exists a chamber 25, the use of which will be alluded to hereinafter. The lower end 90 of the guide tube 24 is housed in a casing 26 assembled with the closure 3 and located within the tank 1. The casing 26 preferably is closed at its bottom, as shown at 27, the function of the casing 26 being to prevent 95 the liquid in the tank 1 from disturbing the float 34 (hereinafter described) when the liquid slushes about in the tank 1. In order that the liquid in the tank may find access to the float 34, the casing 26 is provided adjacent its lower end with openings 28. Openings 29 are formed in the casing 26 adjacent the upper end thereof to permit the egress of air from the casing. The guide tube 24 may be provided, near to the closure 105 3, with openings 30, to permit the egress of air from the guide tube.

The invention comprises a plunger, de-

2
noted generally by the numeral 31, and constructed as desired. In the present instance, but not necessarily, the plunger is a composite structure and includes a rod 32 mounted to reciprocate in a bearing 33 carried by the lower end of the guide tube 24. The float 34 is attached to the lower end of the rod 32 and operates in the casing 26. The plunger 31 comprises a bar 35 united by a swivel connection 36 with the upper end of the rod 32, the bar being mounted to reciprocate in the guide tube 24 and in the top of the barrel 8. It may now be stated that the chamber 25 serves to collect the fluid which may happen to be carried upwardly through the guide tube 24 by the action of the plunger 31. A nut 37 is threaded on the upper end of the bar 35 and includes a reduced neck 38 having a detachable flange 39. The numeral 40 marks a bridge disk of conducting material and adapted to engage with the contact terminals 9, the bridge disk having an upwardly bulged boss 41 loosely engaged about the neck 38 of the nut 37 and held by the flange 39. Since the bridge disk 40 thus is loosely mounted on the nut 37, the bridge disk will, of a certainty, contact with both of the terminals 9 when the plunger 31 moves downwardly. The nut 37 preferably is held in place by a lock nut 42, threaded upon the upper end of the bar 35. A stop 43 is attached to the barrel 8 and includes a laterally extended end 44 adapted to coact with the nut 42 when the plunger 31 rises under the action of the float 34.

In practical operation, a predetermined quantity of liquid is placed in the tank 1, the float 34 rising under the action of liquid. The plunger 31 rises along with the float. The nut 37 is moved downwardly along by the bar 35 until the bridge disk 40 engages both of the terminals 9 and closes the circuit of which the conductor 15 constitutes a part. The nut 37 is then held in the position to which it has been adjusted, by manipulating the lock nut 42. By the procedure above outlined, the structure is so set that it will give a signal when the liquid in the tank 1 has been depleted to the predetermined quantity fixed upon experimentally.

When the tank 1 is filled with liquid, the float 34 rises, carrying with it the plunger 31, the nut 42 engaging the end 44 of the stop 43, the upward movement of the float and the plunger being limited in this way, and the bridge disk 40 being held out of contact with the terminals 9.

When the liquid in the tank 1 is drawn away to a sufficient extent so that the predetermined quantity of liquid remains in the tank, then the float 34 and the plunger 31 move downwardly until the bridge disk 40 engages the terminals 9. Then the circuit is closed, the signal 20 is sounded, and the lamp 16 is lighted, the lamp illuminat-

ing the front 18 of the receptacle 17 and rendering the inscription 19 visible. The operator thus is advised by an audible signal and by a visible signal, that the liquid in the tank 1 has been used down to a predetermined amount. It is obvious that either the lamp 16 or the signal 20 may be omitted, at the will of an operator.

It is not necessary that the plunger be actuated by the specific float construction shown in Fig. 1. Thus, referring to Fig. 4, the numeral 45 marks a plunger, corresponding to the part 31 and engaged at its lower end by one end of a lever 46 fulcrumed on a support 48, and provided at its other end with a float 47.

Having thus described the invention, what is claimed is:

1. In a device of the class described, a tank; a barrel carried by the tank; contact terminals at the upper end of the barrel; a signal circuit of which the terminals form a part; a plunger mounted to reciprocate in the barrel; a float in the tank and controlling the operation of the plunger; a bridge adapted to cooperate with the terminals; and means for mounting the bridge on the plunger for swinging movement and for adjustment longitudinally of the plunger with respect to the terminals. 95

2. In a device of the class described, a tank; a neck carried by the tank; a barrel mounted in the neck; binding means engaging the neck and the barrel; a signal circuit of which the binding means constitutes 100 a part; contact terminals at the upper end of the barrel and engaged with the binding means; a plunger mounted to reciprocate in the barrel; a float in the tank and operatively connected with the plunger; and 105 a bridge carried by the plunger and co-operating with the terminals.

3. In a device of the class described, a tank; a barrel carried by the tank; a guide tube mounted in the barrel and terminating short of the top of the barrel to form a collecting chamber; a plunger mounted to reciprocate in the guide tube; a float in the tank and operatively connected with the plunger; contact terminals carried by 110 the barrel, the upper end of the barrel inclosing the plunger closely to form a top closure for the chamber, thereby preventing liquid which accumulates in the chamber from reaching the terminals; a signal circuit of which the contact terminals constitute a part; and a bridge carried by the plunger and coacting with the terminals. 120

4. In a device of the class described, a tank; a barrel carried by the tank; a cap; means for holding the cap on the barrel; contact terminals mounted in the barrel; a signal circuit of which the contact terminals form a part; a plunger mounted to reciprocate in the barrel; a float in the tank 130

and operatively connected with the plunger; a bridge carried by the plunger and adapted to engage the terminals; and a stop carried by the barrel and having an end overhanging the plunger to limit the upward movement thereof, the stop being independent of the cap and being located therewithin.

5. In a device of the class described, a tank; a depending casing carried by the top 10 of the tank; and having an air vent disposed close to and beneath the top of the tank; a guide tube carried by the tank and extended downwardly into the casing, the tube being spaced from the casing; a plunger mounted 15 to reciprocate in the guide tube; a float operatively connected with the plunger and disposed within the casing; a barrel about the upper end of the guide tube; contact terminals carried by the barrel; a signal 20 circuit of which the contact terminals form a part; and a bridge mounted on the plunger

and adapted to coact with the contact terminals.

6. In a device of the class described, a tank; a barrel carried by the tank; contact terminals at the upper end of the barrel; a signal circuit of which the terminals form a part; a plunger mounted to reciprocate in the barrel; a float in the tank and controlling the operation of the plunger; a nut threaded on the plunger; and a bridge swiveled to the nut whereby the bridge will coöperate with the terminals when the nut is rotated to adjust the bridge longitudinally of the plunger with respect to the terminals. 25

In testimony that I claim the foregoing as my own, I have hereto affixed my signature in the presence of two witnesses.

JESSE T. CURTIS.
